CLARENCE H. BROWN, OF BRIDGEPORT, CONNECTICUT, ASSIGNOR TO UNDERWOOD
TYPEWRITER COMPANY, OF NEW YORK, N. Y., A CORPORATION OF DELAWARE.

TYPE-WRITING MACHINE.

1,137,115.

Specification of Letters Patent. Patented Apr. 27, 1915.

Application filed March 6, 1913. Serial No. 752,269.

To all whom it may concern:

Be it known that I, CLARENCE H. BROWN, a citizen of the United States, residing in Bridgeport, in the county of Fairfield and State of Connecticut, have invented certain new and useful Improvements in Type-Writing Machines, of which the following is a specification.

My invention relates to typewriting machines, and is particularly directed to relieving the machine of some of the shock to which it is ordinarily subjected in line-spacing operations.

Another object is to provide means for adjusting such line space mechanism; and to provide means for rendering the operation of such mechanism more accurate. To bring about these results, a spring is interposed between the platen and the usual ratchet wheel by which the platen is rotated. There preferably are two such springs symmetrically arranged, which normally hold the platen in a given position by keeping an arm fast on said platen against an abutment fast on the line-spacing wheel. Said abutment is preferably adjustable and by such adjustment the tension of the springs and the alinement of the line-space wheel with the platen may be altered. When said alinement is so altered, it brings the wear on the platen in a new place, and thus said adjustment furnishes means for distributing the wear on a platen uniformly over its surface. The mechanism also may comprise a stop which co-operates with the driving pawl of the line-space mechanism, in such a way that it is impossible for said pawl to overthrow the line-space wheel, and if the usual detent for holding the line-space wheel in position is used, the mechanism becomes positive in operation.

Other features and advantages will hereinafter appear.

In the accompanying drawings, Figure 1 is a perspective view of so much of the shiftable platen frame of an Underwood typewriting machine as is necessary to understand my invention as applied thereto. Fig. 2 is an end view of the same. Fig. 3 is an end view showing the parts during a stroke of the line-space lever. Fig. 4 shows the parts at the end of a stroke. Fig. 5 is a section showing some of the parts

seen in Fig. 1. Fig. 6 is a perspective view 55 of the adjustable abutment.

In the Underwood typewriting machine, types 1 strike against the front of a platen 2, which platen is rotatably mounted in a shiftable frame 3 by means of an axle 4 60 journaled in said frame. Said axle has journaled thereon a line-space wheel 5 which is arranged to be engaged by a pawl 6, said pawl carried on a slide 7 and operated by an arm 8 of a lever 9, in the usual manner. 65 Said pawl is normally drawn forward by means of a spring 10 to the position seen in Fig. 1, from which position, when the lever 9 is operated, said pawl will be driven backwardly and turn the line-space wheel 70 5 through a number of spaces determined by a slide 11. Said line-space wheel has fast thereon a stop 12 against which bears one arm 13 of a bell crank 14 pivoted at 15 on an arm 16 fast to the axle 4 of the platen, 75 said bell crank arm 13 being drawn against stop 12 by means of a spring 17 anchored at 18 in another arm 16 extending from the platen axle, so that as said line-space wheel 5 turns, the stop 12 bears against the bell 80 crank arm 13, and by means of the spring 17, draws the platen axle around with it. Preferably there are two stops 12, each bearing against similar arms 13 on bell cranks 14, which are symmetrically arranged 85 around the platen.

It will be seen that if the line-space lever 9 is violently operated, the pawl 6 in turning the line-space wheel 5 will tend to make the stops 12 revolve the bell cranks 14 90 around the pivots 15, thus drawing on the springs 17, and that said springs may be of such tension that they will only start the platen slowly. Said springs are limited in turning the line-space wheel 5 around the axle by means of an abutment 19 which is shown in the form of a screw 20 having an eccentrically mounted head 21 thereon. Said screw fits tightly in a threaded socket in the line space wheel 5, so that it will remain in any position in which it is set, and therefore adjustably hold the adjacent arm 16 at any required angle to the line-space wheel 5 within the limits of the eccentricity of its head 21.

The action of the parts may be summed up as follows, so far: The pawl 6 starts to revolve the line-space wheel so that it

stretches the springs 17 and tends to carry the abutment 19 clear of the adjacent arm 16. The springs 17, however, immediately begin to revolve the platen, and bring it up with the line-space wheel so that the said adjacent arm 16 bears against the abutment 19. The line-space wheel 5 has bearing against it the usual spring pressed 5 to the detent 22 which serves to bring said line-space wheel to rest at the proper point, and the pawl 6 has thereon an extension 23, which at the limit of its throw rides under a projection 24 of the shiftable frame 3, thus locking the pawl 6 against the line-space wheel 5 and preventing the line-space wheel from being overthrown. This arrest of the line-space wheel positively arrests the platen by means of the abutment 19, for if the springs 17 are properly 10 portioned they will bring the platen up with the line-space wheel before the operator can release the line-space lever 9.

The abutment 19, it will be noted, may be utilized for varying the tension of the 15 springs 17. Thus, as seen in Fig. 4, where the head of said abutment has been rotated to bring its axis of greatest eccentricity against the arm 16, the springs 17 are greatly stretched, while in Fig. 2, where the 20 other axis of the abutment is adjacent the arm 16, the springs 17 are comparatively slack. This adjustment also alters the alignment of the teeth of the wheel 5 with the platen, and thus alters the point at 25 which the type strike the platen, so that by adjusting the abutment 19, the point of wear on the platen may be altered.

Variations may be resorted to within the 30 scope of the invention, and portions of the 40 improvements may be used without others.

Having thus described my invention, I 35 claim:

1. In a typewriting machine, the combination 45 with a revoluble platen and a line space wheel loose on the axle thereof, of an arm fast on said axle, a lever pivoted on said arm, a stop on said wheel bearing against 50 said lever, and a spring connecting said lever and said arm.

2. In a typewriting machine, the combination 55 with a revoluble platen and a line space wheel loose on the axle thereof, of an arm fast on said axle, a lever pivoted on said arm, a stop on said wheel bearing against 60 said lever, an abutment on said wheel against which said arm bears, and a spring connecting said lever and said arm.

3. In a typewriting machine, the combination 65 with a revoluble platen and a line space wheel loose on the axle thereof, of an arm fast on said axle, a lever pivoted on said arm, a stop on said wheel bearing against 70 said lever, a spring connecting said lever and said arm, and an adjustable abutment on said wheel against which said arm

bears, whereby the tension of said spring may be varied.

4. In a typewriting machine, the combination 75 with a revoluble platen and a line space wheel loose on the axle thereof, of arms extending radially from said axle, oppositely extending levers pivoted on said arms, stops on said wheel bearing against said levers, springs connecting said arms and levers, and an abutment on said wheel bearing against one of said arms.

5. In a typewriting machine, the combination 80 with a revoluble platen and a line space wheel loose on the axle thereof, of a pawl for driving said line space wheel, arms extending radially from said axle, oppositely 85 extending levers pivoted on said arms, stops on said wheel bearing against said levers, springs connecting said arms and levers, an overthrow stop limiting the throw of said line-space wheel, and an abutment on said wheel bearing against one of said arms.

6. The combination with a platen and a line space wheel loose on the axle of said platen, of arms fast on said axle, a bell 90 crank pivoted on one arm, a platen-driving spring extending from said bell crank to the other arm, a stop on said wheel limiting the throw of said bell crank by said spring, and an abutment on said wheel limiting the 95 throw of said arm over said wheel.

7. The combination with a platen and a line-space wheel, of connecting means between said platen and said line-space wheel, including a member fast to said platen, a 100 yielding connection between said line-space wheel and said member to enable said line-space wheel to rotate the platen to line-space a work-sheet thereon, and adjustable means to limit the movement of said member 105 to vary the relative positions of said platen and line-space wheel, whereby the printing line position of the platen may be changed.

8. The combination with a platen and a 110 lever, of connecting means to enable the lever to rotate the platen to line-space a work-sheet thereon, said connecting means including a part yieldable to permit the lever when quickly operated to move in advance of the platen, and adjustable means 115 associated with said yielding part for re-aligning the line-spacing movements of the platen.

9. The combination with a platen and a 120 lever, of connecting means to enable the lever to rotate the platen to line-space a work-sheet thereon, said connecting means including a part yieldable to permit the lever when quickly operated to move in advance of the platen, and adjustable means 125 for arresting the platen at the conclusion of its line-space movement.

10. The combination with a platen and a lever, of connecting means to enable the 130

- lever to rotate the platen to line-space a work-sheet thereon, said connecting means including a part yieldable to permit the lever when quickly operated to move in advance of the platen, a stop for limiting the stroke of the lever, and adjustable means independent of said stop for arresting the platen at the conclusion of its line-space movement.
10. 11. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including a platen-driving spring between said wheel and platen; and an adjustable device carried by said wheel to vary the relative normal positions of said wheel and platen.
12. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including an arm fixed to said axle, a member movably mounted on said arm, a stop on said wheel bearing against said member, and a platen-driving spring connecting said member and said arm.
13. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including an arm fixed to said axle, a member movably mounted on said arm, a stop on said wheel bearing against said member, a platen-driving spring connecting said member and said arm, and an adjustable device carried by said wheel to vary the relative normal positions of said wheel and platen.
14. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including an arm fixed to said axle, a member movably mounted on said arm, a stop on said wheel bearing against said member, a platen-driving spring connecting said member and said arm, and an adjustable device carried by said wheel to vary the relative normal positions of said wheel and platen.
15. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including an arm fixed to said axle, a member movably mounted on said arm, a stop on said wheel bearing against said member, a platen-driving spring connecting said member and said arm, and a device mounted on said wheel and adjustably engaging said arm to vary the relative normal positions of said wheel and platen.
16. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including an arm fixed to said axle, a member movably mounted on said arm, a stop on said wheel bearing against said member, a platen-driving spring connecting said member and said arm, and a cam mounted on said wheel and adjustably engaging said arm to vary the relative normal positions of said wheel and platen.
17. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including an arm fixed to said axle, a bell-crank pivoted to said arm, a stop on said wheel bearing against one arm of said bell-crank, and a platen-driving spring connecting the other arm of said bell-crank and said fixed arm.
18. In a typewriting machine, the combination with a revoluble platen to frictionally feed a work-sheet, a line-space wheel loose on the platen axle, and a manually-operable line-space lever to rotate said wheel; of driving means connecting said wheel and said platen for transmitting the movement of the wheel to the platen and controlling the initial speed of the platen, said driving means including an arm fixed to said axle, a bell-crank pivoted to said arm, a stop on said wheel bearing against one arm of said bell-crank, and a platen-driving spring connecting the other arm of said bell-crank and said fixed arm.

movement of the wheel to the platen and controlling the initial speed of the platen, said driving means including an arm fixed to said axle and extending transversely thereacross, a bell-crank pivoted to one end of said arm, a stop on said wheel bearing against one arm of said bell-crank, and a platen-driving spring connecting the other arm of said bell-crank and the other end of 10 said fixed arm.

19. In a typewriting machine, the combination with a revolute platen to frictionally feed a work-sheet, a line-space wheel loose on the platen axle, and a manual

operable line-space lever to rotate said 15 wheel; of driving means connecting said wheel and said platen for transmitting the movement of the wheel to the platen and controlling the initial speed of the platen, said driving means including a platen-driving spring between said wheel and platen; and means adjustable to vary the relative 20 normal positions of said wheel and platen.

CLARENCE H. BROWN.
